PRINTING PRESS

Edward Wolff, New York, N. Y.

Application November 24, 1937, Serial No. 176,275

3 Claims. (Cl. 101—314)

The present invention has relation to printing presses and the main object of this invention is to provide a miniature press operating as a useful and instructive toy.

5 The improved miniature press is so designed that all the essential parts of an operating press are included whereby a comparatively inexperienced juvenile person may therewith effect printing on cards or sheets of a size within the 10 capacity of the press.

With this miniature press most of the parts thereof are made of sheet metal stamped out and so arranged and constructed that these parts may be produced and assembled at a comparatively 15 low cost so that the press can be sold at a low price as an operating and useful toy. The construction and design of the press is such that the packing and handling of the press is facilitated. Furthermore, the design is attractive in 20 appearance which may tend to materially aid in the sale of the press.

The invention consists mainly of the particular construction and arrangement of the component parts or elements of the improved structure as 25 will be hereinafter more fully described with reference to the accompanying drawing wherein:

Figure 1 is a plan view of the improved press, and

Figure 2 is a side elevation thereof.

30 Referring to said drawing, as previously stated the improved press has all the essential parts which render the construction useful for practical printing in a moderate way, and accordingly the improved press shown in the drawing 35 comprises a supporting frame composed of a pair of sheet metal side members 1 and 2 having turned in stiffened edges 3. These members for strength and appearance are united by rivets 4 to form an X-shaped structure. Said members 40 are secured to and supported on a base 5. The means for securing said members together and to the base 5 comprises cross-bars 6 secured by bolts to said base 5.

45 The operative members of the improved press include the operating table 7 which is secured at each side by block 8 and pins 9 to the upper ends of the supporting members 1. Inking pad 10 is mounted and secured on the upper ends of the 50 supporting members 2. The type block 11 carrying type is also mounted on the upper ends of the press 2 and is arranged to slide vertically in a slideway defined by turned in portions 12 and this block is held in position by a wire 13 secured to the block and bearing on the holder 14

for the inking pad 10. The block 11 is grooved horizontally so as to receive the type 15.

With the simplest and most economical form of the improved press preferably rubber type 5 would be employed and the type block is preferably made of wood. The block 11 closely fits within the slideway or track holding the same whereby an even impression can be obtained in the printing operation. It will be understood, however, in a more expensive form of the improved press metal type and a metal block would be employed so as to get fine adjustment for better printing.

The improved press has the platen 16, which is connected by a system of links 17 with the 15 inking roller 18 and operating lever 19 in such a manner that on the upward movement of said lever the sheet on the platen will be brought in contact with the type and in the same movement the inking roller 18 is caused to travel over the 20 inking pad 10. When the lever 19 is brought to its down position the inking roller picks up ink on the pad and inks the type for the next impression. To insure perfect contact of the inking roller with the type 11 pressure is exerted by the spring 20.

The particular link system as shown comprises 25 companion links 21 on each side of the frame and pivoted thereto at 22. The links 21 are connected together by a tie-bar 23 so as to operate 30 in unison. The links 21 at the free ends are pivotally connected to hangers 24 which carry the inking roller 18. Links 25 pivoted on links 21 are pivotally connected to a strip 26 secured on the under side of the platen 16. A single centrally located connecting rod or link 27 is pivotally connected to a crank 28 and which crank is carried by the shaft 29 to which the operating lever 19 is secured. The mechanism or working 35 parts of the printing press are so constructed and arranged that an equalized movement is given to the platen and inking roller so that an even pressure of the platen and inking of the type is obtained and thereby the operator may, besides 40 having the amusement, produce useful printing 45 work.

Various modifications may be made in carrying out the details of the invention hereinbefore described, and it is to be understood that any modification coming fairly within the terms of 50 the appended claims shall be covered thereby.

I claim:

1. A printing press of the class described comprising a supporting frame, an oscillating platen, an inking roll, a hand lever for operating said 55

- platen and roll, a link system coupling said lever with said platen and said inking roll, said link system comprising a crank device operated by said lever, a pivoted link connection between said 5 crank and said platen, a pair of links pivoted one on each side of said frame carrying said inking roll, a pivoted link connection between said platen and each of said inking roll carrying links and a tie bar uniting the latter links together.
- 10 2. A printing press of the class described comprising a supporting frame, an oscillating platen, an inking roll, a hand lever for operating said platen and roll, a link system coupling said lever with said platen and said inking roll, said link system comprising a crank device operated by said lever, a pivoted link connection between said crank and 10 said platen, a pair of links pivoted one on each side of said frame carrying said inking roll, a pivoted link connection between said platen and each of said inking roll carrying links, a tie bar uniting the latter links together, said frame 15 comprising a pair of side members mounted on a supporting base and said members being each composed of a pair of crossed sheet metal plates united together.
- 15 3. A printing press of the class described comprising a type block, an inking device, a supporting frame, an oscillating platen, an inking roll, a hand lever for operating said platen and roll, a link system coupling said lever with said platen and said inking roll, said link system comprising a crank device operated by said lever, a pivoted link connection between said crank and 10 said platen, a pair of links pivoted one on each side of said frame carrying said inking roll, a pivoted link connection between said platen and each of said inking roll carrying links, a tie bar uniting the latter links together, said frame 15 comprising a pair of side members mounted on a supporting base and said members being each composed of a pair of crossed sheet metal plates united together.

EDWARD WOLFT. 20
